ADJUSTABLE CHAIR CONSTRUCTION

Robert H. Sperring, Oak Park, Ill., assignor to
 N. T. Shepherd Chair Company, Salt Lake City,
 Utah, a corporation of Utah

Application February 16, 1951, Serial No. 211,384

9 Claims. (Cl. 155—157)

1

This invention relates to adjustable chair constructions and more particularly to adjustable posture type chairs.

In posture type chairs as heretofore manufactured, either the seat or the back has been adjustable to fit the chair to a particular user. The adjustable part has usually been held in its adjusted position by a spring latch or the like arranged beneath the seat or at the back of the chair, and in this position it is inconvenient to reach the latch if adjusting the chair. Such latches also require that the user be in a position remote from the normal sitting position when making adjustment so that frequently it is necessary to try a number of adjustments to be sure the proper one is found.

It is one of the objects of the present invention to provide a chair in which the seat and back can be quickly and conveniently adjusted relative to each other to fit the user. According to one important feature of the invention, the adjustment can be made from a position closely adjacent to the normal sitting position.

Another object is to provide a chair which is normally held firmly against relative movement of the parts and which can be released for adjustment merely by raising the seat slightly.

Still another object is to provide a chair in which the parts are held against relative movement by a reduced circular tip on the supporting post fitting into an axially aligned circular recess so that there will be no interference with swiveling of the chair.

The above and other objects and advantages of this invention will be more readily apparent from the following description when read in connection with the accompanying drawing, in which:

Figure 1 is a side elevation of a chair embodying the invention;

Figure 2 is a partial vertical section through the supporting post with parts in elevation;

Figure 3 is a partial plan view on the line 3—3 of Figure 2;

Figure 4 is a partial section similar to Figure 2 of an alternative construction.

The chair is illustrated as an office type posture chair having legs 10 supported on casters 11 and carrying a central base member 12. The legs as seen in Figure 2 may extend into the base member to be secured thereto by welding or the like and the legs and base member together support a central sleeve or collar 13. A main supporting post 14 is slidable in the collar 13 and is provided with a series of spaced perforations 15 to receive a spring latch member 16 so that the elevation of the chair can easily be adjusted.

At its upper end the post is slidably received in a sleeve 16 which is attached to a channel shaped guide bracket 17 rigidly secured to the bottom of a seat plate 18. The seat plate 18 may

2

be padded or upholstered as indicated at 19 in Figure 1 in the usual manner. As seen in Figure 2 the sleeve fits into an opening in the bottom of the bracket 17 so that the post can extend completely to the seat plate.

A back support 21 is provided which is preferably adjustable on an angular supporting member 22 which may be formed of a relatively strong metal strap or bar bent intermediate its ends. The back support 21 is carried by the vertically projecting end of the bar and the lower horizontal portion thereof extends slidably through the guide space between the seat and the channel shaped bracket 17. The lower horizontal end of the bar is formed with a series of spaced circular openings or recesses 23.

At its upper end, the post 14 is tapered inwardly and terminates in a circular tip 24 of a size to fit slidably in the openings 23. When the seat is in its lowered position as shown in Figure 2, the tip 24 will fit into one of the openings and will hold the supporting member 22 rigidly against sliding. At this time the weight of the user is borne by the upper end of the post 14 through the seat plate 18 so that the guide 16 is required to carry only lateral or bending stress and does not carry the weight.

To release the supporting member 22 for adjusting movement, the seat can be elevated slightly to remove the reduced tip 24 from the registering opening 23 so that the supporting member can then slide freely in the channel shaped bracket. Preferably the post is provided with an annular groove 25 and a pin 26 is carried by the sleeve 16 to project into the groove to limit raising of the seat relative to the post. It will be noted that the supporting member can be released very easily with the user in a position very close to the usual sitting position so that the desired adjustment can be effected rapidly and accurately. With the seat in its lowered position it can swivel freely about the post since the reduced tip and the opening into which it fits lie on an extension of the post axis. Thus, a very simple construction is provided by which the desired adjustment of the back can be made quickly and conveniently.

Figure 4 illustrates an alternative construction in which the seat itself is adjustable. In this figure parts corresponding to like parts in Figures 1—3 have been indicated by the same reference numerals plus 100. As shown, the sleeve 116 carries a supporting plate 117 on which the seat plate 118 is slidably mounted. As illustrated, the seat plate 118 carries offset bracket members 127 which slidably fit over the edges of the supporting plate 117 although any other slidable guide means could be employed. In this construction, the back support, not shown in Figure

4, may be rigidly attached to or form an extension of the supporting plate 117.

To hold the seat plate in adjustable position, it is formed with a series of circular spaced recesses 123 to receive the reduced tip 124 of the supporting post. As illustrated, the recesses are formed by pressing upward the material of the seat plate although they could be drilled if desired. This construction operates in much the same manner as that of Figures 1-3 to hold the seat plate firmly in adjusted position when the seat is lowered to release it for free sliding adjustment when the seat is raised.

While two embodiments of the invention have been shown and described in detail, it will be understood that these are illustrative only and not to be taken as a definition of the scope of the invention, reference being had for this purpose to the appended claims.

What is claimed is:

1. A chair comprising a base, a supporting post extending upward from the base, a sleeve fitting slidably over the upper end of the post, a guide member carried by the sleeve, and a supporting member slidably carried by the guide member, and formed with a series of spaced recesses therein, the upper end of the post being formed to fit into the recesses to hold the supporting member against sliding.

2. A chair comprising a base, a supporting post extending upward from the base, a sleeve fitting slidably over the upper end of the post, a guide member carried by the sleeve, and a supporting member slidably carried by the guide member and formed with a series of spaced circular recesses, the upper end of the post being formed with a reduced circular tip to fit into the recesses to hold the supporting member against sliding without interfering with turning of the sleeve and guide member on the post.

3. A chair comprising a base, a supporting post extending upward from the base, a sleeve fitting slidably over the upper end of the post, a guide member carried by the sleeve, and a supporting member slidably carried by the guide member and formed with a series of spaced circular recesses, the upper end of the post being formed with a reduced circular tip to fit into the recesses to hold the supporting member against sliding without interfering with turning of the sleeve and guide member on the post, the post having an annular groove therein, and a reduced pin on the sleeve projecting into the groove to limit axial sliding of the sleeve on the post.

4. A chair comprising a base, a supporting post extending upward from the base, a seat, a channel shaped guide member secured to the bottom of the seat, a sleeve projecting down from the guide member and fitting slidably over the upper end of the post and a back support including an elongated bar fitting slidably in the guide member and formed with a series of spaced recesses, the upper end of the post being formed to fit into the recesses to hold the bar against sliding.

5. A chair comprising a base, a supporting post extending upward from the base, a seat, a channel shaped guide member secured to the bottom of the seat, a sleeve projecting down from the guide member and fitting slidably over the upper end of the post, and a back support including an elongated bar fitting slidably in the guide mem-

ber and formed with a series of spaced circular recesses, the upper end of the post being formed with a reduced circular tip to fit into the recesses to hold the bar against sliding without interfering with turning of the seat on the post.

6. A chair comprising a base, a supporting post extending upward from the base, a seat, a channel shaped guide member secured to the bottom of the seat, a sleeve projecting down from the guide member and fitting slidably over the upper end of the post, and a back support including an elongated bar fitting slidably in the guide member and formed with a series of spaced circular recesses, the upper end of the post being formed with a reduced circular tip to fit into the recesses to hold the bar against sliding without interfering with turning of the seat on the post, the post having an annular groove therein adjacent to its top, and a reduced pin on the sleeve projecting into the groove to limit axial sliding of the sleeve on the post.

7. A chair comprising a base, a supporting post extending upward from the base, a sleeve fitting slidably over the upper end of the post, a guide plate carried by the sleeve, a seat slidably carried by the guide plate and having a series of recesses therein in a line parallel to its direction of sliding and registering with the top of the post, the top of the post being formed to fit into the recesses to hold the seat against sliding.

8. A chair comprising a base, a supporting post extending upward from the base, a sleeve fitting slidably over the upper end of the post, a guide plate carried by the sleeve, a seat slidably carried by the guide plate and having a series of circular recesses therein in a line parallel to its direction of sliding and crossing the axis of the post, the upper end of the post being formed with a reduced circular tip to fit into the recesses to hold the seat against sliding without interfering with turning of the guide sleeve and seat on the post.

9. A chair comprising a base, a supporting post extending upward from the base, a sleeve fitting slidably over the upper end of the post, a guide plate carried by the sleeve, a seat slidably carried by the guide plate and having a series of circular recesses therein in a line parallel to its direction of sliding and crossing the axis of the post, the upper end of the post being formed with a reduced circular tip to fit into the recesses to hold the seat against sliding without interfering with turning of the guide sleeve and seat on the post, the post having an annular groove therein, and a reduced pin on the sleeve projecting into the groove to limit axial sliding of the sleeve on the post.
